DESIGN FOR AN ARTICLE DISPLAY CASE

Thomas J. Pilliod, Swanton, Ohio, assignor to
The Pilliod Cabinet Company, Swanton, Ohio,
a corporation of Ohio

Application March 29, 1937, Serial No. 68,462

Term of patent 14 years

To all whom it may concern:

Be it known that I, Thomas J. Pilliod, a citizen of the United States and resident of Swanton, in the county of Fulton and State of Ohio, have invented a new, original, and ornamental Design for an Article Display Case, of which the following is a specification, reference being had to the accompanying drawing, forming a part thereof.

Fig. 1 is a perspective view of an article display case embodying the invention, and Fig. 2 is a section on the line 2—2 thereof.

In the drawing, the part shown in full lines comprises sliding cover members A, A of flexible transparent material extending over and in curved lines around the opposite ends of an article supporting part B of the case.

I claim:

The ornamental design for an article display case, substantially as shown and described.

THOMAS J. PILLIOD.
